REMOVABLE CONTACT TIP

Roslyn V. H. Russell, Niagara Falls, N. Y.

Application June 17, 1931, Serial No. 545,049

10 Claims. (Cl. 200—166)

The present invention relates to contact tips and more particularly to removable contact tips adapted to be attached to the type of contact finger used in connection with the drum type controllers. An example of such finger is disclosed in my co-pending application, Serial No. 530,175, filed April 15, 1931.

An object of my invention is to provide a tip which may be removed from the contact finger, 10 or reversed, with the minimum of effort.

A further object of my invention is to provide a contact tip which is simple in construction and which can be manufactured at a minimum cost.

A further object of my invention is to provide 15 a contact tip which is positively held against rotational movement with respect to the finger to which it is secured.

Other objects, features and advantages will appear as the description proceeds.

20 In the drawing wherein I have illustrated one form of my invention,

Figure 1 is a cross-sectional view thereof.

Figure 2 is a cross-sectional view of the copper tip member.

25 Figure 3 is a perspective view of said tip member.

Figure 4 is a detailed view of the bolt which is employed for securing the tip in position.

Figure 5 is a detailed view of the special form 30 of locating washer, and

Figures 6 and 7 are plan and sectional views respectively of a modification.

Referring to the drawing, reference numeral 35 10 designates a contact tip preferably of hard-drawn copper, which is secured to the supporting member 11 of the contact finger. Between members 10 and 11 is a laminated copper strip 12 which serves as a current conductor. The tip 10 is secured to the supporting member 11 by

40 means of a bolt 13, preferably of hardened steel, having a head 14 and a nut 15. A lock-washer 15—a is employed to prevent nut 15 from becoming loosened. The manner in which the tip 10 is secured to the bolt 13 constitutes an

45 essential feature of my invention. Looking at Figures 2 and 3, it will be noted that the tip 10 is provided in the central portion of the upper surface thereof with a recess 16. Bolt head 14 is provided with a lower portion 17 and an upper

50 portion 18 and between said portions there extends an annular groove 19. The lower end of portion 17 is beveled as indicated at 17—a. The diameter of said portion is equal to or very slightly greater than the diameter of recess 16. The diameter of portion 18 is sufficiently greater than

that of recess 16 so that it overhangs the edge of said recess. Portion 18 is preferably hexagonal in cross-section to prevent rotational movement thereof after same has been secured in position on the recess 16.

In securing the tip 10 to the bolt head 14, the latter is placed in a punch press and the tip 10 is placed in an anvil having a recess into which said tip fits in such a manner that recess 16 is in registry with the bolt 13. As the punch press is moved downwardly, the portion 17 of the bolt head will enter recess 16 and be moved downwardly therein, the periphery of said portion being in tight frictional engagement with the wall of said recess. The under surface of top portion 18 will engage with the portion of the tip immediately surrounding recess 16. Further downward movement of the bolt 13 will cause the metal, which is overhung by portion 18, to be forced downwardly into the annular recess 19 and at the same time, the lower portion 17 of the bolt head 14 will be firmly embedded in the lower portion of the recess 16. I have found that in a tip constructed in the manner described, the metal which is forced into the annular recess 19 positively locks the bolt in position and prevents removal of the same from the tip.

In order to prevent rotational movement of the tip about the finger 11, I have provided the tip at its upper surface with a pair of transverse slots 20. Located on the bolt 13, between the nut 15 and the supporting member 11, is a washer 21 of the type illustrated in Figure 5. It will be noted that the washer is provided with a pair of depending side flanges 22 and a front flange 23 which is slightly longer than the side flanges 22. The lower edge of flange 23 is adapted to fit in one of the grooves 20 and thus prevent rotational movement of the tip. The construction is given further rigidity by flanges 22 which extend downwardly in contact with the edges of members 11 and 12.

In Figures 6 and 7 I have shown a modification in which, instead of a groove 20, a pair of short grooves 24 are provided adjacent either end of the tip. The forward end of the supporting member 11—a is bifurcated and the two protruding bifurcations are bent downwardly to fit within said short grooves 24 and thus prevent rotational movement of said tip.

In the assembly of tip 10 with bolt 13 the latter is placed in an inverted position in the anvil. It will be obvious from the above that as the punch press descends, it will force portion 17 of bolt head 14 into recess 16 and in tight engagement

with the wall thereof. In fact, as the bolt is preferably made of steel and the tip is of copper, the action of the punch press on said bolt results in its being entirely embedded in the softer metal.

5 Bevel 17—a permits of more easy passage of the bolt head into the recess 16. The portion 18 of said bolt head, however, being of greater diameter than said recess 16, will engage the metal constituting the upper edge thereof and carry it 10 downwardly under the pressure of the ram. As said metal is relatively soft, it will flow into groove 19 and, as above pointed out, constitute a means for positively locking the bolt in position in the tip.

15 From the above it will be seen that I have provided a tip which is extremely simple to manufacture and which is rigidly held in operating position. When the tip becomes slightly worn on the one side, it may be reversed merely by loosening the nut 15 sufficiently to permit the lower edge of flange 23, or of the bifurcated portions of member 11—a, as the case may be, to clear the upper edge of the slots provided to receive them, when the tip may be turned at will. To remove 20 the tip it is only necessary to remove the nut 15 from bolt 13.

The washer 21, co-operating with the slot 20, absolutely prevents rotational movement of the tip 10 with respect to the finger 11. The side flanges 22 of the washer, prevent the latter from 30 rotational movement during the tightening of the nut 15. It will thus be seen that I have provided an extremely simple arrangement whereby the position of the tip 10 with respect to the finger 11 35 cannot be varied from that desired.

An important advantage of my invention is that when the nut 15 is turned to tighten the tip in position, there is no tendency to pull the bolt-head 14 from its embedded position in the tip 10, 40 due to the fact that the upper surface of portion 18 of the bolt-head bears directly against the under surface of the conductor 12. As the nut is turned, the conductor 12, supporting member 11 and washers 15—a and 20 are compressed between 45 the nut and said portion 18 of the bolt-head. Obviously, if the portion 18 were omitted, the tendency upon the tightening of the nut 15 would be to pull the bolt-head 14 from its position as shown in Figures 1 and 7, which would result 50 in loosening of the bolt-head from the tip 10 to permit rotational movement of the tip 10 relative to the bolt.

In the drawing I have illustrated one form of my invention. Many modifications will occur to those skilled in the art. I intend this patent to cover all such modifications that come within the scope of the appended claims.

What I claim as new and desire to protect by Letters Patent is—

60 1. A contact tip comprising an integral piece of metal in combination with securing means embedded therein, said securing means having spaced horizontally extending portions with a recess therebetween embedded in said contact tip, a portion of said tip being interposed between said spaced portions whereby said securing means is positively held in position in said tip.

70 2. A contact finger comprising a supporting member, a contact tip adapted to be supported thereby, a member embedded in said contact tip for securing said contact tip to said supporting member, and means adapted to fit over a portion of said supporting member and to interlock with 75 said contact tip to prevent rotational movement

of said contact tip with respect to said supporting member.

3. In a contact finger, a supporting member, a contact tip having a recessed face for engaging the supporting member, and means rigid with the supporting member and engaging the recess in the contact tip for positively preventing rotational movement of said contact tip with respect to said supporting member and linear movement longitudinally or laterally of said supporting member.

4. In a contact finger tip, a supporting member, a contact tip having a recess formed therein, means for securing said contact tip to said supporting member, and means adapted to engage a portion of said supporting member and the walls of said recess to prevent rotational movement of said contact tip with respect to said supporting member.

5. In a contact finger, a supporting member having an aperture, a contact tip having a recess formed therein adapted to be supported by said supporting member, a bolt having its head embedded in said contact tip adapted to extend through said aperture to hold said contact tip in position, and a washer having a pair of side flanges adapted to engage said supporting member, and an end flange adapted to enter said contact tip recess for positively preventing rotational movement of said contact tip with respect to said supporting member.

6. A contact tip in combination with securing means comprising a shank for engagement with a supporting member and a head embedded in the tip, said head comprising spaced apart upper and lower portions forming a recess therebetween, said upper portion being of greater area than the lower portion and a part of the tip being interposed in the recess between the upper and lower portions caused by the deformation of the tip by the upper portion when the securing means is longitudinally forced into the tip.

7. A contact tip comprising an integral piece of metal in combination with securing means embedded therein, said securing means having spaced annular flanges with a recess therebetween embedded in said contact tip, one of said flanges being unround to prevent rotation of the securing means with respect to the tip, and a portion of said tip being interposed in the recess between said spaced portions whereby said securing means is held against longitudinal movement in said tip.

8. A contact tip comprising an integral piece of metal in combination with securing means embedded therein, said securing means having spaced horizontally extending portions and a recess therebetween embedded in said contact tip, with a portion of said tip interposed in said recess, the upper surface of one of the spaced horizontally extending portions being flush with the top surface of the tip and forming a continuous surface therewith, whereby the stresses incident to the securing of said tip to said supporting member are prevented from being transmitted to the embedded portion of said securing means.

9. In a contact finger, a contact tip, a supporting member therefor, said contact tip being recessed on its surface engaged by the supporting member, and a washer adapted to fit over a portion of said supporting member and having side flanges for engaging the sides of the supporting member, said washer also having a front flange adapted to fit over the front end of the supporting

member and engage the recess in the tip for holding the tip from movement with respect to the supporting member.

10. In a contact finger, a supporting member having extending lugs angularly disposed with respect to the plane of the member, a contact tip having a flat surface for engagement with the sup-

porting member and recessed for engagement by the lugs on the supporting member, and securing means for holding the tip in position on the supporting member, whereby the tip is positively prevented from rotary or longitudinal movement with respect to the supporting member. 5
